CLAIM

The ornamental design for package for dart board, as shown and described.

DESCRIPTION

FIG. 1 is a perspective view of a package for dart board showing my new design;

FIG. 2 is a rear perspective view thereof;

FIG. 3 is a top plan view thereof;

FIG. 4 is a bottom plan view thereof; and,

FIG. 5 is a left side elevational view thereof; the right side elevational view being a mirror image thereof.

Fig. 4.

Fig. 5.
